UNITED STATES PATENT OFFICE

2,651,975

INTERNAL CARVING MACHINE

Milton Soloff, Flushing, N. Y.

Application May 11, 1949, Serial No. 92,601

5 Claims. (Cl. 90—11)

1

This invention relates to a machine and method for producing artistic and ornamental effects by drilling within transparent plastic.

It has long been known that artistic representations of objects in three dimensions can be produced by drilling a cavity conforming to the shape of the object within a transparent plastic member. The drilled portion, when viewed from the outside of the block, appears to be the object enclosed therein. Heretofore, this work has been done by hand in a time consuming and expensive manner.

Accordingly, it is an object of this invention to provide a machine for automatically carving a transparent plastic block so as to produce an ornamental effect therein.

Another object of this invention is to provide a machine for simultaneously carving a plurality of transparent blocks.

A further object of this invention is to provide a machine for carving a plurality of plastic blocks which may be successfully operated by unskilled workers.

A feature of this invention is its novel vise cradle which enables the designs to be generated within the plastic.

Another feature of this invention is its multiple stage construction, which permits a plurality of identical designs to be formed simultaneously.

A further feature of this invention is its completely automatic operation which greatly speeds the cutting time required.

A feature of this invention is its novel cam operation which enables this machine to simulate hand carved objects.

The invention consists of the construction, combination and arrangement of parts, as herein illustrated, described and claimed.

In the accompanying drawings, forming a part hereof, is illustrated one form of embodiment of this invention, in which drawings similar reference characters designate corresponding parts, and in which:

Figure 1 is a view in side elevation of a complete embodiment of the internal carving machine, according to this invention.

Figure 2 is a horizontal sectional view taken on line 2—2 of Figure 1, looking in the direction indicated by the arrows.

Figure 3 is a horizontal sectional view taken on line 3—3 of Figure 1, looking in the direction indicated by the arrows.

Figure 4 is a fragmentary view, somewhat enlarged, of a vertical section, taken through the cradle assembly.

Figure 5 is a fragmentary sectional view, somewhat enlarged, of a drilled plastic block, according to this invention.

Figure 6 is a view in perspective of the work holding mechanism.

Figure 7 is a diagrammatic top plan view of a

2

flower carved within a plastic block, according to this invention.

Referring to the drawings, and particularly Figures 1 and 2, 10 indicates a support member such as a bench top upon which are mounted two spaced vertical columns 11. A beam 12 is slidably mounted upon the columns 11 and normal thereto. The said beam 12 spans the distance between the columns 11. Counterweights 13 secured to chains 14 are provided at each end of the beam 12. The chains 14 are looped over and engaged by a sprocket wheel 15 which in turn is carried by a shaft 16 freely turnable within pillow blocks 17 upon the upper portion of each of the columns 11.

A pin 18 is secured to the shaft 16 at right angles to the longitudinal axis thereof. The pin 18 is engaged by a push rod 19 which is disposed in parallel alignment with the columns 11, and extends through an opening 20 in the table 10.

Immediately below the table 10, there is located a motor 21 having a suitable gear reduction mechanism 22 connected thereto. A cam 23 is secured to the output shaft 24 of the gear reduction mechanism 22. The push rod 19 rides upon the periphery of the cam 23 so that the rotation of the cam 23 is translated into a rotation of the shaft 16 and a consequent raising and lowering of the beam 12 by the operation of the chains 14, sprockets 15 and counterweights 13.

A plurality of drilling stations 25 are provided upon the beam 12. All of these stations 25 may be powered by a single motor 26 and belts 44, as shown in Figure 1, or by individual motors, if desired. Suitable chucking devices 27 are provided to hold cutters 28 for machining the work parts 29.

The work parts 29, which may comprise any suitable transparent plastic, such as Lucite, are each held in a vise 30, best shown in Figures 3, 4, 5. Each vise is rotatable through 360° by reason of being attached to a swiveled gear member 31. All of the gears 31 are in mesh so that the rotation of one of them as by the motor 32 and reduction gear 33 will turn them all.

The entire vise assembly is carried upon a crank-shaped cradle member 34. Two spaced upright supports 35 are provided on the bench top 10 for the purpose of receiving the ends 36 of the cradle 34. The right hand support 35 also carries a motor 37 and a reduction gear train 38. A large gear 39 is freely mounted upon the shaft 36 of the cradle 34 in front of the right hand upright 35. The gear 39 is provided with a plurality of openings (not shown) to receive the end of a pin 40. The pin 40 is carried in a bore 41 in the cradle 34 so that as the motor 37 drives the gear train 38 which in turn rotates the large gear 39, the cradle 34 will be rotated through an arc of approximately 90°.

The vises 30, best shown in Figure 6, are so

constructed that the work part 29 held therein will always be centered as the jaws are closed. It is also necessary to hold the work parts 29 so that their upper or drilling faces 46 are in line with the pivotal axis of the cradle 34.

It has been found desirable to decrease the speed of the cradle 34 as it approaches the upper portion of its swing. For this purpose a rheostat 43 or suitable means for slowing down the motor 37 may be provided, coupled to the large gear 39, as shown in Figures 1 and 3.

From the foregoing description of the carving mechanism, its operation may be traced as follows:

The work pieces 29 are grasped firmly within the vises 30 and the drill motor 26 started. The drills are allowed to cut into the work parts until the cam 23 raises them. The three motors 21, 32 and 37 are started and the carving of the design proceeds simultaneously in each of the work parts 29. The path of the cutters 28 is substantially helical as a result of the circular and cradled action of the work holding mechanism. The depths of the cut at each stage of this helical travel is determined by the shape of the cam 23. A wide variety of designs may be carved in the above manner by changing the speeds of the motors and the shape of the cam 23. When the carriage 34 reaches the top of its travel, the cutters 28 are withdrawn from the work parts 29 and the motors 21, 32 and 37 stopped. The pin 48 is withdrawn from its contact with the gear 39 and the cradle 34 allowed to swing down to the bottom of its path. The fully carved pieces 29 then may be removed from the vises 30 and polished. The face of the work piece 29 opposite that drilled will permit the carved design 45 to be viewed, as shown in Figure 7.

It is within the purview of this invention to insert a vibrator 47 between the elements of the push rod 19, as shown in Figure 1. The vibrator 47 will impart a continuous motion to the pin 48, which in turn will result in a slight vertical movement of the cutters 28. The resultant vertical movement of the cutters 28 will produce a striated effect within the flowers, said effect giving them a more realistic appearance.

Having thus fully described the invention, what is claimed as new and desired to be secured by Letters Patent of the United States, is:

1. A drilling machine comprising in combination a base support member, a column mounted upon said base, a tool support member slideable axially with respect to said column, means for moving the tool support axially of the column, a work support means mounted upon the base, a swingable cradle member below the tool support having the work support means rotatably secured thereto, means to swing said cradle through an arc, tool means on said tool support, means to simultaneously turn said tool, rotate the work support and reciprocate the tool support in timed relationship with each other and the cradle swing.

2. A drilling machine comprising in combination a base support member, a column mounted upon said base, a tool support member slideable axially with respect to said column, means including a power source, a cam driven by said power source and a link between the cam and tool support for moving the tool support axially of the column, a work support means mounted upon the base, a swingable cradle member below the tool support having the work support means rotatably secured thereto, means to swing

said cradle through an arc, tool means on said tool support, means to simultaneously turn said tool, rotate the work support and reciprocate the tool support in timed relationship with each other and the cradle swing.

3. A drilling machine comprising in combination a base support member, a column mounted upon said base, a tool support member slideable axially with respect to said column, means for moving the tool support axially of the column, a work support means mounted upon the base, a swingable cradle member below the tool support having the work support means rotatably secured thereto, means comprising a cradle power source and a rheostat connected thereto to control the swing of said cradle through an arc, said rheostat being activated by the swing of the cradle member, tool means on said tool support, means to simultaneously turn said tool, rotate the work support and reciprocate the tool support in timed relationship with each other and the cradle swing.

4. A drilling machine comprising in combination a base support member, a column mounted upon said base, a tool support member slideable axially with respect to said column, means including a power source, a cam driven by said power source and a link between the cam and tool support for moving the tool support axially of the column, a work support means mounted upon the base, a swingable cradle member below the tool support having the work support means rotatably secured thereto, means comprising a cradle power source and a rheostat connected thereto to control the swing of said cradle through an arc, said rheostat being activated by the swing of the cradle member, tool means on said tool support, means to simultaneously turn said tool, rotate the work support and reciprocate the tool support in timed relationship with each other and the cradle swing.

5. A drilling machine comprising in combination a base support member, a column mounted upon said base, a tool support member slideable axially with respect to said column, means for moving the tool support axially of the column, a work support means mounted upon the base, a swingable cradle member having a substantially U-shaped structure, said cradle being journaled at each end thereof below the tool support having the work support means rotatably secured thereto, means to swing said cradle through an arc, tool means on said tool support, means to simultaneously turn said tool, rotate the work support and reciprocate the tool support in timed relationship with each other and the cradle swing.
